US00D443828S

(12) **United States Design Patent** (10) Patent No.: **US D443,828 S**
 Meeker et al. (45) Date of Patent: ** Jun. 19, 2001

(54) **BEVERAGE BOTTLE**

- (75) Inventors: **Shane Edwin Meeker**, Maineville, OH
 (US); **Peter Brian Clarke**, Fairfield,
 CT (US)
- (73) Assignee: **The Procter & Gamble Co.**,
 Cincinnati, OH (US)
- (**) Term: **14 Years**
- (21) Appl. No.: **29/111,999**
- (22) Filed: **Oct. 7, 1999**
- (51) LOC (7) Cl. **09-01**
- (52) U.S. Cl. **D9/540; D9/552**
- (58) Field of Search **D9/537, 540, 552,**
D9/549, 558, 545, 548, 300; 215/382, 383,
384

(57) **CLAIM**

The ornamental design for a beverage bottle, as shown and described.

DESCRIPTION

FIG. 1 is a perspective view of a beverage bottle, embodying our new design;
 FIG. 2 is a top view thereof;
 FIG. 3 is a left side elevational view thereof;
 FIG. 4 is a front elevational view thereof; the back elevational view thereof being a mirror image;
 FIG. 5 is a right side elevational view thereof;
 FIG. 6 is a bottom view thereof;
 FIG. 7 is a perspective view of an alternative embodiment of the beverage bottle;
 FIG. 8 is a top view thereof;
 FIG. 9 is a left side elevational view thereof;
 FIG. 10 is a front elevational view thereof; the back elevational view thereof being a mirror image;
 FIG. 11 is a right side elevational view thereof; and,
 FIG. 12 is a bottom view thereof.

The broken lines in the drawings are for illustrative purposes only and do not form part of the claimed design.
